UNITED STATES PATENT OFFICE.

AARON A. BROWN AND JAMES A. LARSH, OF CINCINNATI, OHIO; SAID LARSH ASSIGNOR OF FOUR-FIFTHS TO SAID BROWN.

MACHINE FOR SEWING ON BUTTONS.

SPECIFICATION forming part of Letters Patent No. 340,536, dated April 20, 1886.

Application filed August 7, 1885. Serial No. 173,853. (No model.)

To all whom it may concern:

Be it known that we, AARON A. BROWN and JAMES A. LARSH, of Cincinnati, in the county of Hamilton and State of Ohio, have 5 invented certain new and useful Improvements in Machines for Sewing on Buttons, of which the following is a specification.

Our invention relates to a machine for sewing buttons onto a fabric, and it is especially 10 designed for sewing shoe-buttons onto a shoe fabric. It is especially adapted to carry out a process and make the stitch set forth in Letters Patent of the United States No. 300,206, granted Aaron A. Brown, June 10, 1884, and 15 we have shown the construction and arrangement adapted to this particular stitch, but the mechanism is adapted to make other forms of stitches by slight mechanical adjustments or manipulations of the operating devices.

20 One of the objects of our invention is to sew a button onto a fabric by making a double-loop stitch over the button and eye, and pulling the loop-thread, drawn through the eye down on the double below the eye, then reversing the position of the button and making 25 the same loop from the opposite side and drawing it down and around the first loop.

Another object of our invention is to automatically operate and control the button and 30 draw the thread over the button, so as to make a knot or loop below the eye of the button, thereby securing it firmly to the fabric, and to sew the buttons on in a continuous series.

Other features of our invention relate to the 35 details of construction of the machine, and will be fully set forth in the description of the accompanying drawings, forming a part of this specification, in which—

40 Figure 1 is a side elevation of our improved machine. Fig. 2 is a side elevation opposite to that of Fig. 1. Fig. 3 is a top plan of the same. Fig. 4 is a front elevation of the same. Fig. 5 is a plan view of the clamp-jaws, showing the moving cam and its connections in elevation. Fig. 6 is a detailed section, partly in elevation, of one of the clamp-jaws. Fig. 7 is a side elevation of the clamping-jaws, moving cam, and connections. Fig. 8 is a side elevation of the needle-arm clamping mechanism 45 and operating-cam. Fig. 9 is a side elevation 50

of the cam for operating the clamp-jaws. Fig. 10 is a side elevation of the cam operating the thread-feeding arm or looper. Fig. 11 is a side elevation of the cam-link and crank-connections for operating side clamps and the 55 front top clamp for holding the button in a fixed position. Fig. 12 is a detailed view of the crank-arms supporting and moving the clamp-jaws shown in section. Fig. 13 is a detailed view of the front clamp. Fig. 14 is a 60 detailed view of the foot for holding under edge of the button. Fig. 15 is a detailed view of the thread-releasing device. Fig. 16 is a side elevation of the thread-releasing mechanism and its operating-cam. Fig. 17 is a side elevation of the thread take-up cam and driving-lever. Fig. 18 is an elevation showing parts 65 and position for pulling the first loop through the eye of the button, with one of the jaws removed. Fig. 19 is a similar view showing 70 the position of the parts completing the first loop or stitch. Fig. 20 is a front elevation showing the position of the jaws and button when it is being pulled through the loop to form a stitch. Fig. 21 is a detailed view of 75 needle and thread-releasing hook when the first loop is drawn through the eye of the button. Fig. 22 is a similar view showing second 80 position of the parts for releasing the thread from the needle. Fig. 23 represents the third 85 position of the parts in the act of slipping the thread off the hook of needle. Fig. 24 shows the button and fabric drawn away for the stitching for a second button.

A represents base or frame-work of the machine, on which the operative parts are mounted and supported. It is preferably made of cast-iron having sides A' or flanges extending backward, for supporting the main driving-shaft B, which is journaled on said side extension, A'.

All the leading movements of the machine are obtained from cams keyed upon said shaft, which, for convenience, we have formed on the opposite side of disks a b c d e. The configuration of these cams formed on these disks are shown in the elevation by Figs. 5, 7, 8, 9, 10, 11, 16, and 17. These several cams are shown in position which they severally occupy in starting the first movement for forming the 90 95 100

stitch, and they separately work out the movement in one complete revolution of the main shaft B. These movements and the details of construction are as follows.

5 C represents the horn on which the fabric is supported. Its forward end is slotted and receives the needle-feeding bar or looper, which is a reciprocating bar operated by arm C'', to which it is connected by a bolt passing through 10 a slot in said horn, Fig. 1. This looper is operated by cam shown in Fig. 10.

c'' represents forks projecting back from bar C'', which serve as guides for a friction-roller, c', which is rigidly journaled on a stud 15 projecting from bar C'', said friction-roller traveling in the cam-grooves a'. These two cam-grooves a' produce two movements of the looper-arm to one revolution of the shaft. This double movement is only necessary when 20 two loops or stitches are made in sewing on one button. We design to use the same movement, using only one stitch for a button, and hence one movement of the looper to sew on a button. This movement is made to feed 25 the thread forward and throw it into the needle-hook after the clamping-jaws have clamped the button and carried it into position.

The clamping-jaws D D' are pivoted to a cross-head, D'', which supports a stud, h'', Figs. 2 and 5. These jaws are supported at the front end by crank-arms E E', and held in position, as shown in Figs. 1 and 2, and at the rear end by a sliding bar, d''', which reciprocates in journal-wrist g'', mounted 5 on bracket C''', said bar being rigidly connected to yoke D'', said bar being also attached at its forward end to a cross-piece, d', connecting the lower end of the crank-arms E E', substantially as shown and lettered in Fig. 2.

o The crank-arms E E' are journaled upon a shaft, e', journaling in a sleeve, e'', Fig. 1, said sleeve being the termination of the overhanging arm F, which projects forward from frame A of the machine, as shown in Figs. 1 and 2.

5 E'' represents a slotted crank-arm keyed upon the shaft e'; and E''' represents a connecting-rod engaging by a wrist, e'', in the slot of arm E'', journaling on a center, F'', which is pivoted to arm F', the latter being fulcrumed upon an arm, F''', projecting from the frame of the machine. Its lower end carries a roller, F'', which works in the cam-groove f''', Fig. 11. The construction of this cam and its connections are such that when the main shaft B starts in its revolution it carries the clamping-jaws D D' forward, to hold the button in position under the needle; but the jaws are previously brought together to clamp the button in the following manner: The jaws are slotted through their sides, as at 7, Figs. 1 and 7, and in this slot or mortise is placed a yoke, O'', which has inclining slots, d'', pierced vertically throughout. In each of these slots is a roller, d', journaled on a stud or pin formed on or attached to the jaw D and D', respectively, and running vertically through the slot of the jaw.

H' represents a pitman having its forward end rigidly connected to the cross-head O'', Fig. 5. It rests upon the sustaining-rod d''', 70 This latter, as previously stated, reciprocates in the wrist-journal g'', which sustains the mechanism operated upon and with the jaws D D'. The pitman H' is bent down at its near end, as shown in Fig. 5, and suspended upon 75 a link, H''', which is pivotally connected to the upper end of the stud h''.

g' represents an extension of the pitman H', and it reciprocates in a wrist-journal, g, that journals in the forward end of the bell-crank 8c lever G, the latter being fulcrumed on a pin, g'', on the frame of the machine. Its lower end carries a roller, G', which travels in the cam-slot G'', which slot is so constructed as to give it two reciprocating motions, to give the 85 pitman H' two forward and backward movements with one revolution of the shaft. The rod g' slides freely through the wrist g on lever G, and the reciprocating movement imparted to the said rod by the lever is due to 90 the pivotal connection between the hanger H''' and the stud h''. The first movement is to draw together the jaws D D' to clamp the buttons and hold them in this position until after the needle has drawn the thread through the eye 95 of the button. When the forward movement of the pitman H' moves yoke O'' forward, it opens or spreads the jaws at the right time to permit the button to pass through the loop as it is turned over by the side clamps, 1 1, in 100 the manner about to be shown, one thread of loop passing on either side of button. When the jaws D D' are again brought together to clamp the button, the movement is reversed for making the second stitch, as will be more 105 fully shown hereinafter.

1 represents the side clamps, which are shaped to grasp the edge of the button. These clamps are formed on a stud or short shaft, 2, which journals in the jaws D D'. 110

3 represents a pinion keyed upon each one of these short shafts.

4 represents rack-bars attached to the under side at the end of arms H H'. These racks engage with the pinions 3. The bent shanks 115 of these arms H H' are connected together by a pivot at the heel, and the shank H'' is pivoted to a bell crank-lever, H'', one end of which lever is pivoted to the stud h'', supported by the cross-head g''. (See Fig. 3.) 120

The arms H H' are operated by levers and a cam preferably in the following manner:

5 represents a wrist-pin journaling in the driving-lever 6, through which rests, passes, and reciprocates the shank-rod H''. 125

6 represents a lever-supporting wrist 5, journaled to the frame.

7 represents a roller-journal in the lower end of lever 6 and traveling in the cam-groove 8.

9 represents the stud on which arm 6 is 130 journaled. This cam is of such shape as to reciprocate the arms H H' forward and back once during each revolution of the main shaft B, so as to turn the button over from its posi-

tion shown in Fig. 18 to the position in Fig. 19, which movement completes the first stitch by pulling the thread over the button, and the second movement reverses the button from the position shown in Fig. 19 to the position shown in Fig. 24 for making a second stitch.

10 represents a stationary top clamp, which is attached to a head, 11, connected to bar 13. (See Fig. 2.) This top clamp serves as a pressure-bar for holding the button down. n represents a hook which holds the button in the position shown in Fig. 19.

12 represents a front top clamp, which is likewise pivoted to the head 11 of said bar 13. Its upper end is provided with a slot, 14, in which engages a pin, 15, that projects from crank-arm 16, which crank is journaled to the crank-shaft e'. This crank-pin 15 and arm 16 move the top clamp, 12, forward and upward into the position shown in Fig. 1.

At each movement of the mechanism completing a stitch or loop the action of the side clamps, 11, reverses the position of the button and brings the clamp back again into position on the button to hold it down before the needle is passed through the eye of the button for drawing through the loop. The points h of these clamps 10 and 12 serve the function of opening or spreading the loop of the thread so that the loop may be pulled over the button at the right time, thus avoiding missing a stitch or loop.

17 represents an arm carrying a supporting-hook, 46, which is shown in reversed position in Fig. 14.

18 represents a slot pierced through the shank of said hook.

19 is a pin projecting from clamp 12 into slot 18, and serves as a guide to hold said hook 17 in its proper vertical plane. This supporting-hook 17 obtains its motion from the clamp 12, to which it is connected by the pin 19, Fig. 13, engaging with the slot 18, as set forth, and moves backward and forward simultaneously with it. These clamps 10 and 12 are moved up and down vertically by the bar 13. This bar is moved by a lever, 20, which is preferably operated by means of slot 21, working on a pin or stud, 22, projecting through said slot, and it is operated by the cam-groove 23, in which travels a roller connected to the lower end of arm 20. The shape of this cam is such as to bring the bar 13 down to clamp the button and hold it while taking the first loop or stitch, then to raise it to allow the button to be reversed from the position shown in Fig. 18 to that shown in Fig. 19, then brought down for taking the second loop or stitch, and raised again for releasing the button preparatory to a second operation—that is, the cam 23 raises and lowers the piston 13 twice during each revolution of the main shaft, and the shape of the groove 23 is such as to make the movements quickly at the right point of time.

65 In order to furnish the right amount of thread to form a loop and draw it taut at the right time, we have provided a take-up arm,

24, which journals upon the front side of the frame of the machine, as shown in elevation, Fig. 4.

25 represents the journals, 26, the lower end of the arm, which is bent forward and downward, and pierced with a hole, through which passes the thread L. The thread is held on spool 28, and passes through the eyes 29 in the tension-bar 30, thence through the hole in guide 27, thence through the eye of the take-up lever, thence forward along the line of the horn C under the thread-retaining spring 31, thence forward to the eye 32, and through the eye in the looper C', so as to be engaged by the hook 33 of the needle 34, as shown in Figs. 18 and 19, when the parts take the movements as before described. The shape of the cam 26^a, Figs. 2 and 17, and connecting parts of the take-up bar 26 are such that the arm rises and feeds forward when the needle is at its lowest point, allowing the looper to pull through a sufficient quantity of thread to form one loop, and is then retracted to pull the loop back simultaneously with the pulling the loop over the button after it has been drawn through the eye and engaged by the mechanism before described. (See Sheet 9 of the drawings.) This backward movement is sufficient to pull the thread taut to complete the formation of the stitch, and when two stitches are made by one revolution of the shaft, as herein described, it has a double oscillating motion, caused by the shape of the cam-groove 26^a.

The numeral 35 represents the needle-bar, to the lower end of which the needle is attached.

36 represents the operating-lever, to which the needle-bar is connected by means of a link-rod, 37, passing through the wrist 38, attached to the needle-bar. (See Fig. 8.)

39 represents the pivot connecting said lever 36 to the machine.

40 represents the cam groove in which roller 41 travels, journaling on the lower end of lever 36, to operate the needle-arm. (See Fig. 8.) This cam 40 makes two up-and-down motions of the needle-bar to one revolution of the shaft, so as to pull two loops or stitches through the eye of the button, as will be described hereinafter.

The machine is operated as follows: The fabric to which the button is sewed is laid upon the horn C. A feeding device may be employed to feed the button into the clamps 11 while the jaws D D' are in the act of closing, or the buttons may be fed in by hand. The main shaft B is rotated by hand or power. The first movement of the cam G'' brings the clamps 11 together, engaging the button, and into the position shown in Fig. 18. The needle-bar then thrusts the needle through the eye of the button, as shown in said figure, and the thread feeder or looper C' is thrown forward, bringing the thread L into the hook of the needle, and the needle and its bar are retracted, drawing the loop up through the

fabric and the eye of the button. As soon as the needle is fully retracted, the thread-releasing device shown in Fig. 23 is brought in the position as there shown. It consists of a 5 pivoted deflecting-hook, 41, pivoted to bar 42 and held up by a spring-actuated rod, 41^a, attached forward of the pivotal point and drawing upward, as seen in Fig. 15, and a slotted guard, 43, through which the needle dips 10 slightly, passing through the slot 44, (shown in Fig. 15,) which throws the thread off of the hook, and it slips down onto the thread-releasing hook 41, which drops on its pivot, as shown in Fig. 23, the thread sliding off as the 15 arm 42 is retracted. The retraction of said arm 42 is effected in the following manner: The arm is rigidly mounted upon a yoke, 42^a, pivotally attached to one of the guides of the needle-bar 35. Upon this yoke is formed an 20 arm, 42^b, which extends upward, and is connected by a rod, 42^c, with a lever, 42^d, which is vibrated by a cam, 42^e, on the main shaft. At this instant of dropping the thread off of hook 41 the top clamp-jaws, 10 and 12, are 25 raised to the position shown in Fig. 19; but while the loop is held up by the needle, as shown in Fig. 22, the side clamps, 11, are released by the spreading of the jaws D D', and the button is reversed or turned over into the 30 position shown in Fig. 19. This movement draws the thread over the button, the point h of clamp 10 spreading apart the threads, to allow the button to pass between them. As the thread is slipped off the releasing-hook 41 it 35 drops down onto the eye of the button and slips off over the eye onto the loop-thread below the eye, where it is drawn taut by the backward movement of the take-up arm 26. As soon as the button is brought into the 40 position shown in Fig. 19, the clamps are brought down onto the button to hold it firmly, the needle thrust through the eye of the button and fabric by the second downthrow, and the thread drawn up through the eye of the button 45 ton a second time. The loop-forming mechanism moves forward to form the loop the same as in making the first loop or stitch, in which position the loop is held by the thread-releasing hook 41 momentarily, to allow side 50 clamps, 11, to clamp and reverse the button to its former position, at which movement the thread again slips off of the releasing-hook 41 by a backward oscillation of the bar 42, dropping the thread down over the eye, as in the 55 first operation, when the backward motion of the take-up arm 26 will draw the second thread taut onto the eye of the button and onto the first loop. The slotted bar 43 throws the loop off of the hook of the needle in the same manner for the second stitch as described for the first stitch, and the completion of the revolution of the shaft draws the holding-foot 46, button 47, and the top clamp-jaw, 12, into position shown in Fig. 24, pulling the fabric and 60 the button along, making a space for a second button, and assisting in drawing the loops of the stitches taut to the fabric. A second but-

ton is brought into the clamps 11, and the operation is continued for this and each succeeding button, sewing them onto the fabric in 70 a continuous series with the same thread. The thread can be made very large and strong, so as to obtain a very strong stitch for sewing.

The ordinary sewing-feed may be used to 75 feed the cloth along slightly between the first and second loops, or it may be fed by hand, so as to have the needle go through the fabric for making the second loop or stitch a little in rear of the first penetration. 80

We claim—

1. In a machine for sewing on buttons, the combination, with the reciprocating clamp-jaws D D', of carrying-clamps 1, carried by crank-arms having shafts journaled in the 85 said clamp-jaws, and adapted to hold the button in position for drawing through the first loop or stitch, and mechanism, substantially as described, for rotating the clamp, turning the button, and holding it in position for drawing the second loop through the eye, as substantially herein specified. 90

2. In combination with the reciprocating clamp-jaws D D', a mechanism for driving, opening, and closing the same, the reversing- 95 clamps 11, and the reversing-pinion and rack operated by bars H H', and means, substantially as described, for reciprocating said bars, substantially as herein specified.

3. In a machine for sewing on buttons, the 100 combination, with the stitch-forming mechanism, of the reciprocating clamp-jaws operated by the crank-arms E E', the latter operated by the lever connected to a cam from the main shaft, substantially as herein specified. 105

4. In combination with the clamp-jaws D D' and the clamps 1, the pinions upon the shafts of said clamps, the racks engaging with said pinions, and the reversing mechanism consisting of bars H H', operated by a cam 110 and connection from the main shaft, substantially as herein specified.

5. In combination with the jaws D D', operated by cams on the main shaft, the spreading mechanism O" d' d", operated by a pit- 115 man connected to a lever and driven by the cam G" on the main shaft, substantially as herein specified.

6. In combination with the jaws D D', clamps 1, the oscillating top clamp, 12, operated by the crank-arm 16 simultaneously with the movements of crank-arms E E' and jaws D D', means, substantially as described, for operating the crank-arms E E', the stitch-forming mechanism, and the vibrating sup- 125 porting-hook 17, connected to and operating in unison with the clamp 12, substantially as herein specified.

7. In combination with the clamps 1 and their operating mechanism, the stitch-forming mechanism, the top stationary clamp, 10, and vibrating clamp 12, having their extreme ends pointed, so as to spread the thread for drawing the loops over the button, and the 130

complementary supporting devices holding the button below, substantially as herein specified.

8. In combination with the hook-needle, the stitch-forming mechanism, the thread-releasing mechanism consisting of a guard, 43, pivoted hook 41, attached to the vibrating bar 42, and means, substantially as described, for operating said bar, substantially as herein specified.

9. In combination with the top clamp, 12, and the supporting-hook 46, the hook-needle and complementary stitch-forming mechanism, and means for moving the same in proper relation to said clamp and supporting-hook, substantially as described.

10. In combination with the crank-arms E E', operated by lever and cam mechanism from the main shaft, the jaws D D', the pivotal clamps carried thereby, the reciprocating bar 20 13, carrying the top and supporting clamps operated by a lever and a cam on the main shaft, substantially as herein specified.

11. In combination with the reciprocating jaws D D', operated by cranks and cams on the main shaft, the arms H H', pivoted to bell-crank and connected by reciprocating rod H", moving through the pivoted wrist 5, journaled on the lever 6 and driven by the cam 8, the clamps 1 1, pivotally mounted in said jaws, the pinions on the shanks of said clamps, the racks driving said pinions, and the stitch-forming mechanism, substantially as herein specified.

12. In combination with the jaws D D' and their connecting and driving mechanism, the pitman H', connected to its driving-lever by shank g', reciprocating in the journal-wrist g,

the bell-crank lever carrying said wrist, the cam operating said lever, and the cross-bar O", having inclined slots engaging with pins 40 on the said jaws D D', whereby the pitman is reciprocated independently to open and close said jaws, substantially as herein specified.

13. In combination with the stitch-forming mechanism, means, substantially as described, for supporting and holding the button, the reciprocating jaws D D', the arms H H', having the oscillating wrist-connection to the cam on the main shaft, the reciprocating spreading mechanism operated by pitman H', connected to oscillating and reciprocating mechanism driven by a cam on the main shaft, and crank-arm, lever, and cam-connections of the jaws D D', whereby the three several mechanisms are operated independently from the main shaft simultaneously with the movements of the other parts, and each performing its several functions successively, substantially as herein specified.

14. In combination with the needle-bar and hooked needle, the take-up bar 26, the looper-bar C", having a stud, and the cam a', mounted on shaft B, to feed and draw the thread as the button is presented to the needle in reverse positions by the button-clamping mechanism, substantially as described.

In testimony whereof we have hereunto set our hands.

AARON A. BROWN.
JAMES A. LARSH.
